UNITED STATES PATENT OFFICE.

JESSE A. B. SMITH, OF STAMFORD, CONNECTICUT, ASSIGNOR TO UNDERWOOD TYPEWRITER COMPANY, OF NEW YORK, N. Y., A CORPORATION OF DELAWARE.

TYPEWRITING MACHINE.

Application filed March 31, 1921. Serial No. 457,372.

To all whom it may concern:

Be it known that I, JESSE A. B. SMITH, a citizen of the United States, residing in Stamford, in the county of Fairfield and 5 State of Connecticut, have invented certain new and useful Improvements in Typewriting Machines, of which the following is a specification.

This invention relates to collating devices, 10 and is in the nature of an improvement on the patent to B. C. Stickney, et al., No. 1,295,383, granted February 25, 1919.

In Underwood standard typewriters, feed-rolls to co-operate with the platen are 15 supported by arms or levers loosely mounted on a rod extending from end to end of the platen-frame, and provision is made of a cast-off shaft having flats thereon with which the supporting arms co-operate when 20 the feed-rolls are in their effective positions. This shaft is provided with an arm, usually at its right-hand end, and a link connects the arm to the usual release-lever, actuation of which will rock the cast-off shaft and 25 withdraw the feed-rolls from the platen.

In carrying out the invention, provision 30 may be made of a collating table extending upwardly and rearwardly from the delivery side of the platen and having a side-edge gage at its left-hand edge. Clips may also 35 be provided to hold work-sheets against the collating table near the side-edge gage, and these clips may be yieldably held, as by springs, in either effective or ineffective 40 position. The clips, when in effective position, may be restored to ineffective position by suitable means, such as a bail extending along the same.

The feed-rolls and clips may be controlled 45 by a single manually-operable member, preferably in the form of a pivoted finger-piece. To this end, the cast-off shaft may be provided, preferably at the end opposite to that connected to the cast-off or release-lever, with an arm, and to this arm may be 50 attached a link having a flat or plate-like upper end, a straight edge of which is held in guiding relation with the pivot of the finger-piece by suitable means, such as a spring. Connection between the pivoted 55 finger-piece and the link may be effected by

means of a projection or stud on the former engaging in slots in the flat head of the link. In order to permit release of said cast-off shaft without shifting the finger-piece, the 55 upper end of the link is provided with a vertical slot so that, when the finger-piece is positioned with its stud at the upper end of the slot, the feed-rolls may be cast off by the usual release-lever, the slotted link moving idly with reference to the finger-piece.

To enable the feed-rolls to be cast off or released by the finger-piece, the flat end of the link is provided with a slot leading from the upper end of the first slot and in such a 65 direction that, when the finger-piece is swung to carry the stud into the last-mentioned slot, the link will be lifted sufficiently to cast off the feed-rolls.

Upon the return of the finger-piece to its 70 normal or neutral position with its stud at the upper end of the vertical slot, the feed-rolls will have been restored to their effective position. It may then be desirable to actuate the bail to restore any effectively 75 positioned clip to ineffective position. To this end, the flat upper end of the link is provided with a slot extending from the upper end of the vertical slot and extending in an arc of a circle about the pivot of the 80 finger-piece so that the finger-piece may be shifted without shifting the link to engage a member connected with the bail and actuate the same. It will be seen that, during the movement of the stud through the 85 last-mentioned slot, the link and cast-off shaft will be locked against movement.

Other features and advantages will hereinafter appear.

In the accompanying drawings, 90 Figure 1 is a front view of a portion of an Underwood standard typewriter with the invention applied thereto.

Figure 2 is a sectional view, taken from above, of the mechanism shown in Figure 1, 95 certain parts being omitted.

Figure 3 is a detail view of certain parts shown in Figure 2, indicating the manner in which the clips are yieldably held in either effective or ineffective position.

Figure 4 is a sectional-side view, showing 100 all the parts in their normal positions.

Figure 5 is a view similar to Figure 4, but with the feed-rolls cast off and the clips in closed or ineffective position.

Figure 6 is a view similar to Figure 5, but showing a clip closed.

Figure 7 is a view similar to Figure 6, but with the controlling finger-piece shifted to its extreme forward position, to restore the feed-rolls to effective position relative to the platen, and to return all effectively positioned clips to ineffective position.

A platen 1 is revolvably supported by means of an axle 2, journaled in the ends of a platen-frame 3, and the platen 1 may be rotated either by a hand-knob 4 or by line-space mechanism, comprising a line-space wheel 5.

Work-sheets may be gripped to the platen 1 by means of front and rear feed-rolls 6, the front feed-rolls 6 being carried on a shaft 8, supported by levers 7, which are rotatably mounted on a rod 9, connecting the ends of the platen-frame, and the rear feed-rolls 6 being carried by a shaft 10, supported in levers 11, rotatably mounted on said rod 9. The levers 7 and 11 are provided with downwardly-extending arms 12 and 13, respectively, which normally lie adjacent flat surfaces or flats on a rock-shaft 14. The shaft 14 may be provided at one of its ends, preferably at the right, with an arm 16, which may be connected by a link 17 with the usual cast-off or release-lever 18. Normally, the feed-rolls 6 are held in engagement with the platen 1, as seen in Figure 4, by means of springs (not shown), and, when the cast-off lever 18 is depressed, by means of its finger-piece 19, the link 17 will be drawn upwardly and the rock-shaft 14 turned to the position shown in Figure 5, thereby casting off the feed-rolls.

A collating table or front paper-table 20, having its lower edge adjacent the platen and extending upwardly and rearwardly from the delivery side of the platen, may be supported on the platen-frame in any suitable manner. The collating table is provided at its left-hand edge with a side-edge gage 21, in which are notches 22, to receive suitably-shaped clips 23, rotatably mounted on a rod 24, lying outside of the side-edge gage 21 and parallel thereto, the clips 23 being held in either effective or ineffective position by means of springs 25, secured to the back of the table 20 in position to engage flat surfaces 26 and 27 on the hubs of the clips 23, accordingly as the clips are in effective or ineffective position. The rod 24 is supported in brackets 28, secured to the side-edge gage 21.

In practice, the feed-rolls 6 are in cast-off position while the sheets are being collated or adjusted on the table 20, and the clips 23 are manipulated, in any manner desired, to assist in holding the collated

sheets in position, but, when the feed-rolls are restored to the platen, to enable the collated sheets to be fed forward together, all of the clips should be released. In order to insure release of all the clips when the feed-rolls are restored to the platen, and to obtain co-ordination between the parts, provision may be made of a manually-operable member or handle 32, pivotally mounted on a stud 30 projecting from a bracket 31 on the adjacent end of the platen-frame 3, and having a stud 33 thereon projecting into a three-part slot 34 in a flat portion or plate 35 at the upper end of a link 36, which is connected at its lower end to a second arm 16 at the left-hand end of the shaft 14. The link 36 may be guided in its reciprocating movement by means of a straight edge 37 on the plate 35, which engages the stud 30, and is yieldably held in contact therewith by means of a spring 38, connected at one end to a pin on the plate 35, and at the other end to a pin on the bracket 31.

When the handle 32 is in its normal or neutral position (shown in Figure 4), it will lie at the upper end of a vertical slot 39, forming one branch of the three-part slot 34, and, if the cast-off lever 18 is operated, the link 36 will have an idle movement with reference to the stud 33, the front and rear feed-rolls 6 being cast off in the usual manner. If, however, the handle 32 is depressed from the position shown in Figure 4 to that shown in Figure 5, the stud 33 will move forwardly in a slot 40, substantially at right angles to slot 39, and the link 36 will be raised, so as to cast off the feed-rolls 6, as seen in Figure 5.

The handle 32 may also be used to restore to ineffective position one or both of the clips 23, which may be effectively positioned to hold work-sheets against the table 20. To this end, a bail 41 may be mounted on rod 24 and an arm 42 on the bail connected by a link 43 with a bell-crank-lever 44, mounted on the stud 30, and having a pin 45 extending across the path of the handle 32. When one or both of the clips 23 is depressed, the bail will be shifted to its lowest position, the link 43 will be raised, and the bell-crank-lever 44 shifted to the full-line position, shown in Figure 6. If, then, the handle 32 is restored from its Figure 6 to its Figure 4 position, the feed-rolls 6 will be restored to effective position with the platen, and, upon further movement of the handle 32, the stud 33 will travel along a slot 46, forming part of the three-part slot 34, the slot 46 being so shaped as to be concentric with the stud 30 when the link 36 is in its Figure 4 position, thereby permitting movement of the handle 32 without shifting the link. During this part of its movement,

the handle 32 will engage the pin 45 and move the bell-crank-lever 44 from the position shown in full lines in Figure 6 to that shown in Figure 7, thereby depressing the link 43 and rocking the bail 41 to insure the restoration of clips 23 to ineffective position.

In this connection, it will be seen that, as soon as the stud 33 enters the slot 46, 10 the link 36 will be locked in its depressed position, and actuation of the shaft 14 by the cast-off lever 18 will be prevented. Furthermore, if the link 36 has been lifted due to the actuation of cast-off lever 18, 15 the handle 32 will be locked against movement in the direction to engage pin 45 and restore the clips 23 to their ineffective position. When link 36 has been lifted by means of lever 18 so that stud 33 lies in 20 slot 39, any attempt to actuate handle 32 in a clockwise direction (Figure 4) will urge plate 35 against the fixed stud 30. Although only two clips 23 are disclosed, it is obvious that a larger number may be 25 used if desired.

In practice, a record or proof sheet is kept in the machines and ledger and statement sheets are inserted and collated on the outside thereof when entries are to be 30 made. During this operation, the feed-rolls are in released or cast-off positions so as not to interfere with the relative shifting of the work-sheets, and the clips are shifted as desired to their effective position 35 to hold the collated sheets in position on the collating table. Upon completion of the collating operation, the feed-rolls are restored to the platen and the clips are shifted to ineffective or released position. 40 In order that the work-sheets may always be under control, the mechanism is so designed that handle 32 cannot be moved to a position to release the clips 23 until the feed-rolls 6 are restored to positions to enable them to co-operate with the platen, 45 irrespective of the casting off of the feed-rolls 6 by handle 32 or finger-piece 19. That is to say, the handle 32 when used to cast-off the feed-rolls 6 must be moved 50 to its neutral position to restore the feed-rolls to their effective positions before it can be moved to release any of the clips which may be in effective position, and, if the feed-rolls 6 are cast-off by finger-piece 55 19, handle 32 will be locked against movement to release the clips.

The work-sheets may be inserted at the front of the platen. In this case, the sheets are first placed upon the collating 60 table and gaged under the clips, their lower ends being then slipped down at the front of the platen into the space between the platen and the feed-rolls.

It may be desirable not to place the top 65 sheet, which is to have the ink ribbon im-

pression, under the clips. This sheet may then be held in position on the platen by hand until the feed-rolls, which have stood released during the collating operation, have been restored.

Variations may be resorted to within the scope of the invention, and portions of the improvements may be used without others.

Having thus described my invention, I claim:

1. In a typewriting machine, the combination with a platen, of a collating table at the delivery side thereof, a rod extending along a side edge of said table, a plurality of clip members mounted on said rod for individual movement into and out of position to clamp work-sheets against said table, yielding means to retain the clip members in effective position when so placed, and means to return the effectively-positioned clip members to ineffective position including a bail mounted on said rod, so that when swung from its normal position it will engage all effectively-positioned clips and shift them to ineffective position.

2. In a typewriting machine, the combination with a platen, of a collating table at the delivery side thereof, said table having a side-edge gage, a rod extending along said side-edge gage on the outer side thereof, a plurality of clip members mounted on said rod for individual movement into and out of effective position to clamp work-sheets against the table, and means to restore the effectively-positioned clip members to ineffective position including a bail on said rod which may engage the effectively-positioned clip members, between said rod and said side-edge gage, and restore the same to ineffective position.

3. In a typewriting machine, the combination with a platen and paper-feeding devices bearing upon the same, of a collating table at the delivery side of the platen, a plurality of individually actuatable clip members along one side of the table to hold work upon the latter, cast-off means for said paper-feeding devices, a manually operable member, and means whereby movement of said member to one position will effect restoration of effectively-positioned clip members to ineffective position and simultaneously lock the cast-off means against actuation.

4. In a typewriting machine, the combination with a platen and paper-feeding devices bearing upon the same, of a collating table at the delivery side of the platen, a plurality of individually actuatable clip devices along one side of the table to hold work upon the latter, cast-off means for said paper-feeding devices including a finger-piece for controlling the same, a manually operable member, connections between said cast-off means and said member such

- that in one position of the latter the former may be actuated by its finger-piece without shifting said member, and that when the member is moved to another position the 5 finger-piece may be locked against actuation, and means actuated by said member, in its movement to the last-mentioned position, to shift any effectively-positioned clip device to ineffective position. 70
- 10 5. In a typewriting machine, the combination with a platen, of paper-controlling means comprising paper-feeding devices to bear upon the platen, cast-off means for said devices including a cast-off lever, a 15 manually operable member, and means whereby movement of said member to one position will prevent actuation of said cast-off means, movement to a second position will permit actuation of said cast-off lever, 20 and movement to a third position will actuate said cast-off means. 75
6. In a typewriting machine, the combination with a platen, of paper-controlling means comprising paper-feeding devices to 25 bear upon the platen, cast-off means for said devices including a cast-off lever, a manually operable member, means whereby movement of said member to one position will prevent actuation of said cast-off means, 30 movement to a second position will permit actuation of said cast-off lever, and movement to a third position will actuate said cast-off means, a clip device to hold work which has been inserted in the machine, and 35 means whereby movement of said member to the first position will render said clip device ineffective if effective at that time. 80
7. In a typewriting machine, in combination, a platen, a feed-roll to run thereon, 40 a feed-roll cast-off device, a handle to actuate said cast-off device, a manually operable member, a connection between said member and said cast-off device including a stud on said member, and a shiftable plate 45 slotted to receive said stud, movement of said stud to one position in said plate effecting locking of said device, movement of said member to a second position releasing said device from control of said member, and 50 movement to a third position serving to actuate said cast-off device. 85
8. In a typewriting machine, in combination, a platen, feed-roll mechanism to co-operate therewith, a cast-off shaft to render 55 said feed-roll mechanism ineffective, a pivot, a lever mounted on said pivot, a link connected to an arm of said cast-off shaft and having a flat portion adjacent said pivot, means to hold said link against said pivot 60 for guiding purposes, and a stud on said lever engaging in slots in said flat portion, said slots extending in different directions from a common point, one extending longitudinally of the link to permit reciproca- 65 tion of the latter independently of the lever when the stud is at the common point, another being substantially perpendicular to the first-mentioned slot whereby the link may be actuated by said stud without being forced from its substantially rectilinear path, and a third slot being concentric with the pivot of said lever when the cast-off shaft is in ineffective position, so that the lever may be shifted to move said stud along the third slot without shifting the link. 75
9. In a typewriting machine, in combination, a platen, feed-rolls normally co-operating therewith, a cast-off lever, a device operable by said cast-off lever to cast off said feed-rolls, a collating table at the delivery side of the platen, clips to co-operate with said table supported at one edge thereof, means to yieldably hold said clips in effective or ineffective position, a device universal to said clips to shift effectively-positioned clips to ineffective position, a controlling member so related to said universal device that movement of said member in one direction from its normal position will actuate said universal device, and means 80 whereby actuation of the cast-off device by said cast-off lever will lock said controlling member to prevent actuation thereby of the universal device. 85
10. In a typewriting machine, in combination, a platen, feed-rolls to co-operate therewith, a cast-off finger-piece, a device operable by said finger-piece to cast off said feed-rolls, a collating table at the delivery side of the platen, clips supported adjacent said table to hold work-sheets against the same, a device universal to said clips to shift effectively-positioned clips to ineffective position, a controlling member so related to said universal device that movement of said member from its normal position in one direction will actuate said universal device, and means whereby movement of said member from its normal position in the opposite direction will actuate the cast-off device, said means being such that actuation of said finger-piece will lock said member against movement from its normal position to actuate said universal device, and movement of said member from its normal position in a direction to actuate said universal device will lock said finger-piece against movement from its normal position. 90
11. In a typewriting machine, in combination, a platen, feed-rolls to co-operate therewith, a manually operable cast-off device for said feed-rolls, a collating table extending from the delivery side of the platen, a plurality of releasable clips to hold work-sheets against the collating table, a releasing device universal to said clips, a controlling member having a neutral position and being shiftable therefrom in different directions to two other positions, movement of said member in one of said directions effecting 100
- 120
- 110
- 115
- 125
- 130

actuation of said releasing device, and a connection between said member and said cast-off device whereby the latter may be actuated when said member is in neutral position, but, when actuated, will lock said member against movement to actuate said releasing device, and whereby if said member is moved in the direction to release the clips it will lock said cast-off device, and if said member is moved in the other direction from its neutral position it will actuate said cast-off device.

12. In a typewriting machine, in combination, a platen, feed-rolls to run on the bottom thereof, a collating table at the delivery side of the platen, a plurality of individually-settable clips along one side of the table to hold work-sheets on the latter, feed-roll-cast-off means, a manually-operable member, means whereby movement of said member in one direction from its normal position will actuate said cast-off means, and movement in another direction will lock the cast-off means against actuation, and means whereby the locking movement of said member will restore all effectively-positioned clips to ineffective position.

13. In a typewriting machine, in combination, a platen, feed-rolls to run on the bottom thereof, a collating table at the delivery side of the platen, a plurality of individually-settable clips along one side of the table to hold work-sheets on the latter, feed-roll-cast-off means, a manually-operable member, means whereby movement of said member in one direction from its normal position will actuate said cast-off means, and movement in another direction will lock the cast-off means against actuation, and means whereby the locking movement of said member will restore all effectively-positioned clips to ineffective position, the clip-restoring means being out of the control of said member when said clips are in ineffective position, but being placed under the control of said member when any one of said clips is moved to effective position.

14. In a typewriting machine, the combination with a revoluble platen and feed-rolls to run thereon, of collating means for work-sheets including means for detaining said sheets in collated position, cast-off means for said feed-rolls including a cast-off key, a manually-operable member, and means whereby movement of said member to one position will lock said cast-off key in ineffective position and will render said detaining means ineffective, movement to a second position will permit actuation of said cast-off means and movement to a third position will actuate said cast-off means.

15. In a typewriting machine, the combination with a revoluble platen and feed-rolls to run thereon, of collating means for work-sheets including means for detaining

said sheets in collated position, cast-off means for said feed-rolls including a cast-off key, a manually-operable member, and means whereby movement of said member to one position will lock said cast-off key in ineffective position and will render said detaining means ineffective, movement to a second position will permit actuation of said cast-off means and the consequent locking of said member, and movement to a third position will actuate said cast-off means.

16. In a typewriting machine, in combination, a cylindrical platen and collating means associated therewith, said collating means including a collating table at the delivery side of the platen, a rod adjacent and parallel to one side edge of the collating table, a spring-finger or clip to detain a work-sheet on said table, said spring-finger being pivoted on said rod, spring-means to maintain said finger in effective position or to press the same against the table, and means for swinging said finger from effective to ineffective position comprising a bail pivoted on said rod, said bail being of sufficient length to co-operate with said finger at whatever position the latter may occupy along a considerable portion of the length of said rod.

17. In a typewriting machine, in combination, a platen, feed-rolls to run thereon, a collating table, means to detain collated work-sheets on said table, feed-roll-cast-off means including a finger-piece for actuating the same, a special finger-piece whereby said detaining means may be rendered ineffective, and connections whereby actuation of the cast-off means may be effected by either of said finger-pieces, actuation of the cast-off finger-piece locking the special finger-piece against movement to render the detaining means ineffective, and actuation of the special finger-piece to render the detaining means ineffective locking the cast-off means against operation.

18. In a typewriting machine, in combination, a platen, feed-rolls to run on the bottom thereof, a collating table, means to detain collated work-sheets on said table, means to cast-off said feed-rolls, a finger-piece, and means whereby said finger-piece may either actuate said cast-off means or render said detaining means ineffective.

19. In a typewriting machine, in combination, a platen, feed-rolls to run on the bottom thereof, a collating table, means to detain collated work-sheets on said table, means to cast-off said feed-rolls, a finger-piece, and means whereby said finger-piece may either actuate said cast-off means or render said detaining means ineffective, said cast-off means being locked against operation when said finger-piece is used to render said detaining means ineffective.

20. In a typewriting machine, in combination, a platen, feed-rolls to run on the bot-

tom thereof, a collating table, means to detain collated work-sheets on said table, means to cast-off said feed-rolls, a finger-piece, and means whereby said finger-piece 5 may either actuate said cast-off means or render said detaining means ineffective, said cast-off means being locked against operation when said finger-piece is used to render said detaining means ineffective, and said 10 finger-piece being locked against movement to render said detaining means ineffective by actuation of said cast-off means independent of said finger-piece.

21. In a typewriting machine, in combination, a platen, feed-rolls to run on the bot- 15

tom thereof, a collating table, means to detain collated work-sheets on said table, means to cast-off said feed-rolls, a finger-piece, and means whereby said finger-piece 20 may either actuate said cast-off means or render said detaining means ineffective, said finger-piece being locked against movement to render said detaining means ineffective by actuation of said cast-off means independent of said finger-piece.
